REVERSING COUNTING CHAIN
Glenber L. Hinkle and Lemuel R. Breese, Galion, Ohio,
assignors to North Electric Company, Galion, Ohio, a
corporation of Ohio

Filed Aug. 26, 1960, Ser. No. 24,702
10 Claims. (Cl. 317—140)

This invention is directed to a counting chain circuit and more particularly to such a circuit which is effective to register the receipt of successive impulses for adding to or subtracting from the count, with a simple and economical circuit arrangement having a minimum number of components.

The term "counting chain," as used herein, refers in general to an electrical circuit comprising a number of count-indicating relays, and associated circuitry coupled to such count-indicating relays operable in response to the receipt of successive electrical impulses to energize the count relays to continually provide the total count for the received impulses. Reversing counting chains have been produced to operate either in the forward or reverse direction and thus successively add or subtract the received impulses from the previous total, but such circuits have generally been complex and expensive. It is therefore a primary object of the present invention to provide a reversing counting chain which requires a minimum amount of equipment and is simple both in construction and operation.

It is another object of the invention to provide an instantly reversible counting chain, i.e., a chain which operates either in the forward or reverse direction (to either add or subtract) with respect to each succeeding received impulse and which further is operative in an endless ring.

A further object of the present invention is to provide such a simple counting chain circuit with preset means, in order that any desired number can be preset thereon before the chain is operated in response to received impulses to either add or subtract digits from the preset number.

A preferred embodiment of a counting chain circuit constructed in accordance with the inventive teaching comprises a number of counting chain blocks, each of which comprises both a count relay and an associated sequence relay. Each block includes a series circuit comprising a first and a second contact set controlled by the sequence relay, the winding of the count relay, a set of make contacts carried by the count relay, and the winding of its associated sequence relay which is coupled between supply conductors across which a potential difference is applied. The sequence relay carries, in addition to its first and second contact sets, at least two sets of make contacts, the first set being connected between the line over which forward or additive impulses are applied and the winding of the next higher count relay. Thus, receipt of a forward or additive impulse after operation of the sequence relay in a given block will effect operation of the count relay in the next higher block. The second set of make contacts carried by the sequence relay in the given block is coupled between the conductor over which reverse or subtractive impulses are received and the winding of the count relay in the next lower block of the chain. Thus, responsive to receipt of a reverse or subtractive impulse after operation of the sequence relay in the given block, the count relay in the next lower block will be operated. Such operation lends great versatility to the system, permitting reverse action of the chain even with respect to successive impulses.

Another feature of the invention is the inclusion of preset means, the use of which is effective to operate the respective count relay and its associated sequence relay in

2

any one of the blocks in the counting chain prior to receipt of any impulses. In this manner the received impulses may be either added to or subtracted from the number which was preset on the counting chain.

5 The features of the present invention which are believed to be novel are set forth with particularity in the appended claims. The invention itself, together with further objects and advantages thereof, may best be understood by reference to the following description taken in connection with the accompanying drawings, in the several figures of which like reference numerals identify like elements, and in which:

FIGURE 1 is a schematic diagram depicting a preferred embodiment of the inventive counting chain circuit; and

FIGURE 2 is a partial schematic diagram, useful in understanding the interconnection of a plurality of counting chain banks of the type depicted in FIGURE 1.

The counting chain bank or decade circuit depicted in FIGURE 1 is operable to add or subtract received impulses, the circuit being operable in a continuous ring fashion, so that as the count exceeds nine, the zero count relay is reoperated, and as the count reaches 25, the chain would have been operated through two and one-half complete revolutions, leaving the count relay indicating digit 5 operated after receipt of the impulse which results in a total count of 25. Each digit from 0 to 9, inclusive, is indicated by operation of one of count relays 10-19, respectively, and as will be made apparent by the subsequent explanation, each of count relays 10-19 effects the operation of an associated one of the sequence relays 20-29. Operation of a given sequence relay prepares both the next higher and next lower count relays for operation prior to receipt of the next impulse, and which count relay of the prepared pair is subsequently operated is determined by the nature of the next received impulse, i.e., additive or subtractive.

CIRCUIT OF FIGURE 1—UNITS BANK

40 The counting chain bank of FIGURE 1 has a pair of input terminals 31 and 32; these terminals are indicated as being of positive and negative polarity only to signify that a potential difference is applied over these terminals to energize the components of the counting chain. The 45 polarity of the energizing voltage may be reversed without affecting the operation or components of the counting chain.

A normally-closed reset switch 33 is connected between input terminal 31 and supply conductor 34. Each of the 50 counting chain blocks 0-9, which will be more explicitly defined hereinafter, is coupled between supply conductors 34 and 35, either directly or over intermediate conductors.

55 The forward or add actuating circuit coupled between supply conductors 34 and 35 includes a forward switch 39, the winding of forward relay 40, and break contacts 50a of reverse relay 50. In the drawings a relay winding is depicted by a circle enclosing the reference numeral which designates the relay. The contacts of each relay are not shown adjacent thereto, but are referenced by the same numeral which designates the relay and are specifically identified by a letter suffix. Moreover, make contacts are indicated by an "X" at the junction of the conductors which are connected by closure of such contacts, and break contacts are indicated by a "—" drawn perpendicular to the conductors which are connected over the break contacts. This type of representation, including the contacts detached from the relay winding and the symbols for the make and break contacts, are now well known and understood and are explained in detail in the Bell Laboratories Record of July, 1954, pages

261-266, and in Communications and Electronics, September, 1955, pages 505-513.

Coupled in parallel with the forward or additive actuating circuit is the reverse or subtractive actuating circuit comprising reverse switch 49, the winding of reverse relay 50, and break contacts 40a of forward relay 40. As will be set out more fully hereinafter, each closure of forward switch 39 is effective to advance the counting chain one step by effecting operation of the next higher count relay and releasing the count relay which was operated prior to closure of forward switch 39. In like manner, closure of reverse switch 49 is effective to release the count relay which was operated prior to closure of the reverse switch and to operate the next lower count relay.

A normally open preset switch 38 is connected between supply conductor 34 and preset conductor 36; when switch 38 is closed, a path is completed thereover so that the potential appearing on supply conductor 34 also appears on preset conductor 36. A slider 37 is connected so that one terminal thereof always contacts preset conductor 36, and slider 37 is displaceable along conductor 36 so that the other terminal thereof may contact one of the preset input terminals 60-69 of the counting chain blocks 0-9, each terminal 60-69 being connected to a different one of the blocks. It will be apparent to those skilled in the art that conductor 36 may be the central connection of a rotary wafer switch, and slider 37 may be the displaceable contact of such wafer switch. The manner in which displacement of slider 37 is effective to cause the counting chain to commence operation from any preassigned number will be explained hereinafter.

A set of make contacts 40d of forward relay 40 is coupled between supply conductor 34 and forward (or add) conductor 42. Thus, when relay 40 is operated, contacts 40d are closed and the potential appearing at input terminal 31 and supply conductor 34 is coupled over contacts 40d to forward conductor 42. In like manner, make contacts 50d of reverse relay 50 are coupled between supply conductor 34 and reverse (or subtract) conductor 43, so that operation of reverse relay 50 is effective to close contacts 50d and place reverse conductor 43 at the same potential as that of input terminal 31 and supply conductor 34.

Connected in series between supply conductor 35 and a first hold conductor 45 are two sets of break contacts, 40b and 50b. Thus, when both the forward and the reverse relay are released, first hold conductor 45 is at the potential of supply conductor 35 and input terminal 32; this circuit is interrupted by operation of either forward relay 40 or reverse relay 50. A second hold conductor 46 is connected over a resistor 47 to one side of parallel-connected make contact sets 40c and 50c, and from the other side of these contact sets over supply conductor 35 to terminal 32. Accordingly operation of either relay 40 or 50 is effective to complete the circuit from conductor 46 over the operated one of the contact sets 40c or 50c to supply conductor 35 and terminal 32.

As explained generally hereinbefore, each counting chain block includes both a count relay and an associated sequence relay. The circuitry of the first block, in which the count relay is operated to indicate digit 0, will now be described.

The first counting chain block comprises a count relay 10 and its associated sequence relay 20. Count relay 10 includes a set of make contacts 10a, and sequence relay 20 includes a set of break contacts 20a and four sets of make contacts, 20b, 20c, 20d and 20e. Those skilled in the art will recognize that each count relay may include one or more additional contact sets which may be connected to external equipment, such as indicating lights, control circuits in a computer, or other structure for making use of the particular count indicated in the system of FIGURE 1. Such associated circuitry, however,

is not pertinent to the inventive concept and has therefore been omitted from the drawings.

The lower terminal of the winding of count relay 10 is connected over break contacts 20a to supply conductor 35, and over make contacts 20b to first hold conductor 45. The upper terminal of the winding of count relay 10 is coupled over make contacts 10a and the winding of its associated sequence relay 20 to supply conductor 34. From the series connection of the windings of relays 10 and 20, with make contacts 10a therebetween, it is evident that operation of count relay 10 will close its make contacts 10a and effect energization of its associated sequence relay 20 over a circuit including the winding of the count relay.

Make contacts 20c of sequence relay 20 are connected between forward drive conductor 42 and the winding of next higher count relay 11; operation of sequence relay 20 is thus effective to close contacts 20c and prepare an operating circuit for count relay 11, which circuit can subsequently be completed by closure of contacts 40d in the forward (or add) circuit. In similar fashion make contacts 20d of sequence relay 20 are connected between reverse drive conductor 43 and the winding of next lower count relay 19. Accordingly operation of sequence relay 20 is also effective to close contacts 20d and prepare an operating circuit for count relay 19, which circuit can subsequently be completed by closure of contacts 50d in the reverse (or subtract) circuit. Sequence relay 20 also includes holding contacts 20e connected between the lower terminal of its winding and second hold conductor 46. Each of the other blocks of the chain is constructed and connected in like manner. The operation of the counting chain in response to receipt of a single impulse and specifically a forward or additive impulse, will now be described.

Prior to receipt of any impulse to effect operation of the counting chain, reset switch 33 must be momentarily opened to clear any count then standing in the counting chain (unless, of course, it is desired to add or subtract from such standing count as the system commences operation). Slider 37 must then be positioned to engage one of preset contacts 60-69 and preset switch 38 must be momentarily closed. This procedure is necessary to operate one of the count relays and its associated sequence relay, which sequence relay prepares operating circuits for both the next higher and next lower count relays. For purposes of this initial explanation, it is assumed that a count other than 0 is registered on the chain and it is desired to start from 0, and to tally or register each received impulse by adding it to the starting number (0). Accordingly reset switch 33 is opened and reclosed to ensure that all relays are de-energized, and slider 37 is positioned as shown, between preset conductor 36 and preset terminal 60 of the first (or 0) block.

Closure of preset switch 38 completes an operating circuit for count relay 10, which circuit extends from positive battery over input terminal 31, reset switch 33, supply conductor 34, preset switch 38, preset conductor 36, slider 37, preset terminal 60 of the zero block, the winding of relay 10, break contacts 20a, supply conductor 35, and input terminal 32 to negative battery. Count relay 10 operates, and at its contacts 10a completes an operating circuit for its associated sequence relay 20, which circuit extends from positive battery over input terminal 31, reset switch 33, supply conductor 34, the winding of relay 20, make contacts 10a, the winding of relay 10, break contacts 20a, supply conductor 35, and input terminal 32 to negative battery. Sequence relay 20 operates, and at its contacts 20a interrupts the above-described operating circuits for relays 10 and 20; at its contacts 20b completes a holding circuit over first hold conductor 45 for relays 10 and 20, so that these relays are not released, but are transferred from a circuit including contacts 20a to a circuit including contacts 20b; at its contacts 20c prepares an operating circuit for next higher

count relay 11; at its contacts 20d prepares an operating circuit for next lower count relay 19; and at its contacts 20e prepares a self-holding circuit which can be completed over second hold conductor 45 by subsequent operation of either forward relay 40 or reverse relay 50. The counting chain is now indicating 0 (count relay 10 operated) and is ready to receive and tally incoming impulses.

FORWARD (ADD) OPERATION

To add an impulse or drive the counting chain in the forward direction by one digit, forward switch 39 is closed to complete a previously-described operating circuit for forward relay 40. Relay 40 operates, and at its contacts 40a interrupts the operating circuit for reverse relay 50, to insure that the reverse relay is not operated at this time; at its contacts 40b interrupts the previously-described holding circuit for relays 10 and 20 in block 0; at its contacts 40c completes the previously prepared holding circuit for sequence relay 20, so that only count relay 10 is released at this time; and at its contacts 40d completes the previously-prepared operating circuit for next higher count relay 11, which extends from positive battery over a circuit comprising input terminal 31, reset switch 33, supply conductor 34, contacts 40d, 20c, the winding of relay 11, break contacts 21a, supply conductor 35, and input terminal 32 to negative battery.

Count relay 11 operates, and at its contacts 11a completes an operating circuit for its associated sequence relay 21, which extends from positive battery over input terminal 31, reset switch 33, supply conductor 34, the winding of relay 21, make contacts 11a, the winding of relay 11, contacts 21a, supply conductor 35, and input terminal 32 to negative battery. Assuming switch 39 has opened, relay 40 has released to open contacts 40c and interrupt the holding circuit for sequence relay 20, which also releases.

Sequence relay 21 operates, and at its contacts 21a interrupts the operating circuit for relays 11 and 21 in block 1; at its contacts 21b completes a holding circuit over first hold conductor 35 for relays 11 and 21, so that these relays are not released at this time but are transferred from the circuit including contacts 21a to the circuit including contacts 21b; at its contacts 21c prepares an operating circuit for next higher count relay 12; at its contacts 21d prepares an operating circuit for next lower count relay 19; and at its contacts 21e prepares a self-holding circuit.

If another forward impulse is now provided by closing forward switch 39 and energizing forward relay 40, count relay 12 will be operated and count relay 11 released, and sequence relay 22 will be operated and sequence relay 21 released in a manner which is obvious from the foregoing explanation. Provision of subsequent forward impulses is effective to operate the successive ones of the count relays, until count relay 19 and its associated sequence relay 29 are operated. Relay 29 at its contacts 29c prepares an operating circuit for the next higher count relay 10. Thus the next successive forward impulse effects closure of contacts 40d and completes the operating circuit for count relay 10, and the novel counting chain arrangement operates in an endless ring fashion.

REVERSE (SUBTRACT) OPERATION

Operation of the counting chain in the reverse direction will now be considered. It is initially assumed that preset switch 33 has been momentarily closed with slider 37 set in the position indicated, and that count relay 10 and its associated sequence relay 20 in block 0 have been operated as described hereinabove. Accordingly make contacts 20d, coupled between one side of the winding of next lower count relay 19 and reverse drive conductor 43, have been closed by the operation of sequence relay 20 to prepare an operating circuit for count relay

19, and contacts 20c have also been closed to prepare an operating circuit for the next higher count relay 11.

Reverse switch 49 is closed to complete an obvious energizing circuit for reverse relay 50. Accordingly reverse relay 50 operates, and at its contacts 50a interrupts the energizing circuit for forward relay 40, to preclude any operation of the forward circuit at this time; at its contacts 50b interrupts the holding circuit for count relay 10 and sequence relay 20 which extends over first hold conductor 45, thus causing count relay 10 to release; at its contacts 50c completes a holding circuit for sequence relay 20; and at its contacts 50d completes an operating circuit for next lower count relay 19, which extends from positive battery over input terminal 31, reset switch 33, supply conductor 34, make contacts 50d, reverse drive conductor 43, make contacts 20d, the winding of count relay 19, break contacts 29a, supply conductor 35, and input terminal 32 to negative battery. Relay 19 operates and effects closure of its make contacts 19a. At this time reverse relay 50 has completed its operation; contacts 50b are again closed, and contacts 50c are again open to interrupt the hold circuit for sequence relay 20 which extended over the second hold conductor 45, to restore the same.

Sequence relay 29 operates over a circuit extending from positive battery over input terminal 31, reset switch 33, supply conductor 34, the winding of sequence relay 29, contacts 19a, the winding of count relay 19, contacts 29a, supply conductor 35, and input terminal 32 to negative battery. Relay 29 at its contacts 29a interrupts the energizing circuit for count and sequence relays 19 and 29 and at its contacts 29b completes a holding circuit for these relays over hold conductor 45; at its contacts 29c prepares an operating circuit for next higher count relay 18; at its contacts 29d prepares an operating circuit for next lower count relay 17; and at its contacts 29e prepares a self-holding circuit over second hold conductor 45.

When reverse switch 49 is again closed, reverse relay 50 operates and at its contacts 50d completes an operating circuit for next lower count relay 18, which circuit extends from positive battery over input terminal 31, reset switch 33, supply conductor 34, contacts 50d, reverse drive conductor 43, contacts 29d, the winding of count relay 18, contacts 28a, supply conductor 35, and input terminal 32 to negative battery. Count relay 18 thus operates, and count relay 19 is released by interruption of its holding circuit over first hold conductor 45 at contacts 50b. Count relay 18 in its operation closes contacts 18a to complete an energizing circuit for its associated sequence relay 28, which operates and prepares operating circuits for next higher count relay 19 and next lower count relay 17 in a manner which is obvious from the foregoing explanation. Receipt of additional reverse impulses will effect successive operation of count relays 17, 16, 15, etc., in an obvious manner.

Having started with count and sequence relays 10 and 20 in block 0 operated, after receipt of ten successive reverse or subtractive impulses, the count relays 19, 18, etc. will have been successively operated and relays 10 and 20 in block 0 will again be operated after receipt of the tenth impulse. Accordingly receipt of the eleventh successive reverse impulse effects the actuation of relays 19 and 29 in block 0, and the disablement of relays 10 and 20 in block 0, in exactly the same manner as did the first impulse, and the counting chain of the invention also operates in an endless ring manner when driven in the reverse direction.

RESET OPERATION

Continuous operation in either the forward or reverse direction has been described, with preset slider 37 originally set at preset terminal 60 so that the counting chain commences at 0. Under some circumstances it may be desirable to preset a number on the counting chain and

have the subsequent operations commence from that numerical value. Accordingly operation in both the forward and reverse directions will now be described, commencing with the value 4 preset on the counting chain by movement of slider 37 to engage preset contact 64 of block 4.

If a count was previously registered in the counting chain, reset switch 33 is momentarily opened to de-energize the circuit, thereby effecting the release of the operated counting and sequence relays, and is thereafter reclosed to provide power from input terminal 31 to conductor 34 and to one side of preset switch 38.

To effect presetting of the counting chain, slider 37 is displaced to the right as shown in the drawings until it effects a conductive contact between present conductor 36 and preset terminal 64 of block 4, which block comprises count and sequence relays 14 and 24 and their associated circuitry.

After displacing slider 37 to engage contact 64, preset switch 38 is depressed and an operating circuit for count relay 14 is completed, which circuit extends from positive battery over input terminal 31, reset switch 33, supply conductor 34, preset switch 38, preset conductor 36, slider 37, terminal 64, the winding of count relay 14, break contacts 24a, conductor 35, and input terminal 32 to negative battery. Count relay 14 operates, and at its contacts 14a completes an operating circuit for its associated sequence relay 24, which circuit extends from positive battery over input terminal 31, reset switch 33, supply conductor 34, the winding of sequence relay 24, contacts 14a, the winding of count relay 14, contacts 24a, and supply conductor 35 to input terminal 32. Sequence relay 24 operates, and at its contacts 24a interrupts the operating circuit for relays 24 and 14 in block 4 and at its contacts 24b completes a holding circuit for these relays which extends over contacts 24b, first hold conductor 45, contacts 50b, 40b, supply conductor 35, and input terminal 32 to negative battery; at its contacts 24c prepares an operating circuit for next higher count relay 15; at its contacts 24d prepares an operating circuit for next lower count relay 13; and at its contacts 24e prepares a self-holding circuit which at this time is interrupted at contacts 40c and 50c.

To illustrate the versatility of the counting chain and its ability to operate in either the forward or reverse direction as each successive impulse is received, receipt of three consecutive impulses, a forward impulse, a reverse impulse and then another forward impulse, will now be described. As forward switch 39 is closed to energize forward relay 40, relay 40 operates and at its contacts 40a interrupts the operating circuit for relay 50 to preclude operation of the reverse relay at this time; at its contacts 40b interrupts the holding circuit for relays 14 and 24 in block 4, and at its contacts 40c completes a holding circuit for sequence relay 24 so that only count relay 14 is released; and at its contacts 40d completes a previously prepared energizing circuit for next higher count relay 15, which circuit extends from positive battery over input terminal 31, reset switch 33, supply conductor 34, contacts 40d, forward drive conductor 42, contacts 24c, the winding of count relay 15, contacts 25a, supply conductor 35, and input terminal 32 to negative battery.

Count relay 15 operates and closes its associated make contacts 15a, thus completing an energizing circuit for its associated sequence relay 25 which extends from positive battery over input terminal 31, reset switch 33, supply conductor 34, the winding of sequence relay 25, contacts 15a, the winding of count relay 15, break contacts 25a, supply conductor 35, and input terminal 32 to negative battery. Sequence relay 25 operates, and at its contacts 25a interrupts the operating circuit and at its contacts 25b completes a holding circuit for count and sequence relays 15 and 25; at its contacts 25c prepares an operating circuit for next higher count relay 16; as its contacts 25d pre-

5 pares an operating circuit for next lower count relay 14; and at its contacts 25e prepares a self-holding circuit. By this time forward relay 40 has released, and at its contacts 40c interrupted the holding circuit for sequence relay 24, which releases.

At this stage of the operating sequence, the equipment having been preset to commence operation at numeral 4 (count relay 14 and its associated sequence relay 24 operated), and a single forward impulse having been provided by actuating forward switch 39, the counting chain has been driven to a position in which count relay 15 and its associated sequence relay 25 in block 5 are operated and relays 14 and 24 in block 4 are released. Accordingly the counting chain equipment is now indicating numeral 5.

Reverse switch 49 is now closed to subtract one digit from the indication of the counting chain; reverse relay 50 operates and at its contacts 50d completes an operating circuit for next lower count relay 14 which extends from positive battery over input terminal 31, reset switch 33, supply conductor 34, contacts 50d, reverse drive conductor 43, contacts 25d, the winding of count relay 14, contacts 24a, conductor 35, and input terminal 32 to negative battery. Operation of reverse relay 50 at its contacts 50b interrupts the holding circuit for count relay 15, which releases. Count relay 14 operates, and at its contacts 14a completes a previously-described operating circuit for its associated sequence relay 24. Thus sequence relay 24 operates and prepares operating circuits for both next higher count relay 15 and next lower count relay 13. Reverse relay 50 releases after supplying the reverse impulse and at its contacts 50c interrupts the holding circuit for sequence relay 25, which releases. Accordingly at this time only relays 14 and 24 in block 4 are operated, and operating circuits have been prepared for each of the next higher and lower count relays in a manner described hereinbefore.

Thus, having commenced operation with the equipment indicating numeral 4 by operation of count relay 14, and having added an impulse and subtracted an impulse, the counting chain indicates no net change because count relay 14 is now operated.

Another actuation of forward switch 39 to operate forward relay 40 will cause the operation of relays 15 and 25 in block 5, and the release of relays 14 and 24 in block 4, in a manner previously described in detail. Accordingly count relay 15 and its associated sequence relay 25 will be operated after the receipt of three consecutive impulses, two of which are add or forward impulses and the third of which is a reverse or subtractive impulse. Thus it is evident that the counting chain is operable to instantly reverse its operation from one to another direction, and will provide a net tally of the total number of impulses supplied thereto, no matter the sense (forward or reverse) of each of those impulses.

Reset switch 33 is provided to reset the equipment by returning all of the count and sequence relays therein to the released condition responsive to actuation of the switch. Opening of reset switch 33 interrupts the connection between positive battery at input terminal 31 and supply conductor 34, thereby removing the energizing potential which is requisite to operate not only the forward and reverse relays 40 and 50, but each of the count and sequence relays in the individual blocks of the counting chain itself. After reclosure of the reset switch, the energizing potential is again supplied from positive battery over input terminal 31 to supply conductor 34, and the equipment is conditioned for operation.

CIRCUIT OF FIGURE 2—TENS BANK

70 Those skilled in the art will recognize that a plurality of banks or decades of the type shown in FIGURE 1 can be coupled together to register a larger total than is possible with the single bank there shown. For example, the connection of another similar bank of counting chain blocks to register the tens digit would permit counting

from 0 to 99, rather than from 0 to 9 as is possible with the single bank of FIGURE 1.

The second counting chain bank or decade which may be added to the first to provide for counting from 0 to 99 is the same as the bank depicted in FIGURE 1, except that each of the forward and reverse switches has been replaced by two contact sets. Each of these four added contact sets, designated 10b, 20f, 19b, and 29f in FIGURE 2, is actuated by a corresponding one of count relays 10 and 19 and their associated sequence relays 20 and 29.

As shown in FIGURE 2, the operating circuit for forward relay 140 of the tens bank extends from positive battery over input terminal 131, reset switch 133, make contacts 10b of first count relay 10 in the units bank (FIGURE 1), make contacts 29f of last sequence relay 29 in the units bank, the winding of forward relay 140, break contacts 150a, supply conductor 135, and input terminal 132 to negative battery. Accordingly operation of count relay 19 in the units bank effects operation of its associated sequence relay 29, as explained above. Sequence relay 29 operates and at its contacts 29f (FIGURE 2) prepares an operating circuit for forward relay 140. After receipt of the next forward impulse in the units bank, count relay 10 operates and at its contacts 10b completes the operating circuit for forward relay 140 in the tens bank. Operation of relay 140 steps the tens bank to indicate the next higher digit in a manner obvious from the detailed showing and explanation of the units bank. It is therefore manifest that for each ten forward impulses received by the units bank, relay 140 of the tens bank is operated once.

In similar fashion, the operating circuit for reverse relay 150 of the tens bank extends from positive battery over input terminal 131, reset switch 133, contacts 19b of last count relay 19 in the units bank, contacts 20f of first sequence relay 20 in the units bank, the winding of relay 150, contacts 140a, conductor 135 and input terminal 132 to negative battery. Thus it is evident that a reverse or subtract impulse is transmitted to the tens bank responsive to concomitant operation of first sequence relay 20 and last count relay 19 in the units bank. That is, after count relay 10 and its associated sequence relay 20 are operated in block 0 of the units bank to indicate numeral 0, contacts 20f of sequence relay 20 are closed to prepare an operating circuit for reverse relay 150 in the tens bank. Responsive to receipt of the next reverse impulse in the units bank, count relay 19 is operated over contacts 50d and 20d, thus completing an operating circuit for count relay 19 which operates and at its contacts 19b completes the operating circuit for reverse relay 150 in the tens bank. Accordingly the indication on the tens bank is stepped backward or driven in reverse by one digit, at the same time that the indication in the units bank is stepped backward by one digit.

Suppose that, as an illustrative example, the tens bank is initially indicating numeral 7 and the units bank numeral 0, or a total of 70. Responsive to subsequent receipt of a reverse impulse in the units bank, count relay 10 is released and count relay 19 is operated, thus indicating numeral 9 as the units value, at the same time that the count is stepped in reverse through one digit in the tens bank, from 7 to 6, to indicate numeral 6 as the tens value. Accordingly the combined tens and units counting chain banks now indicate numeral 69, after the subtraction of one digit from the previous total. Thus it is manifest that the connection of contacts 19b and 20f in series with reverse relay 150 in the tens bank is the electrical analogy of the mathematical operation of "borrowing" from the tens column in subtraction, when the units digit of the subtrahend is greater in magnitude than the units digit of the minuend. It is clear that any number of separate counting chain banks or decades can be thus intercoupled, depending on the total to be registered or tallied.

Thus it is evident that the novel reversing counting

chain of the invention does not necessitate the use of relays interconnected so there must be a long sequence of series make or break operations to advance the indication by a single digit. A single bank or decade of the counting chain can be connected to operate in an endless ring fashion, and if a plurality of such banks are connected together, the entire combination can readily be operated in an endless ring even as a single bank or decade of the equipment. The novel chain can easily be driven forward or backward, and its simplicity is evident when it is noted that the sequence relay associated with each count relay utilizes only two contact sets to prepare both the adjoining (next higher and next lower) count relays for operation. Likewise the count relays are of a less complex structure, each requiring only a single set of make contacts to energize its associated sequence relay. Accordingly a simple reversing counting chain has been provided with a minimum of relays and associated circuitry.

20 Although only a particular embodiment of the invention has been shown and described, it is apparent that modifications and alterations may be made therein, and it is intended in the appended claims to cover all such modifications and alterations as may fall within the true 25 spirit and scope of the invention.

What is claimed is:

1. A counting chain comprising: a plurality of counting chain blocks, each of said blocks comprising input means, a count relay operative responsive to receipt of an impulse over said input means, and an associated sequence relay connected for operation responsive to operation of its respective count relay; a first means operable by each of said sequence relays to prepare an operating circuit for the next higher count relay responsive to operation of a given one of said sequence relays; and a second means operable by each of said sequence relays to prepare an operating circuit for the next lower count relay responsive to operation of said given sequence relay.

2. A counting chain comprising: a plurality of counting chain blocks, each of said blocks comprising input means, a count relay operative responsive to receipt of an impulse over said input means, and an associated sequence relay connected for operation responsive to operation of its respective count relay; a first contact set operable by each of said sequence relays to prepare an operating circuit for the next higher count relay responsive to operation of a given one of said sequence relays; and a second contact set operable by each of said sequence relays to prepare an operating circuit for the next lower count relay responsive to operation of said given sequence relay.

3. A counting chain including both forward and reverse drive conductors and further comprising: a plurality of counting chain blocks, each of said blocks comprising input means, a count relay including a winding and a contact set operative responsive to receipt of an impulse over said input means, and an associated sequence relay having a winding series-coupled with said count relay contact set and said count relay winding; a first contact set on each of said sequence relays coupled between said forward drive conductor and the winding of the next higher count relay to prepare an operating circuit for said next higher count relay responsive to operation of a given one of said sequence relays; and a second contact set on each of said sequence relays coupled between said reverse drive conductor and the winding of the next lower count relay to prepare an operating circuit for said next lower count relay responsive to operation of said given sequence relay.

4. A counting chain comprising: a forward drive conductor connected for the selective transmission of forward impulses thereover; a reverse drive conductor connected for the selective transmission of reverse impulses thereover; a plurality of counting chain blocks, each of said blocks comprising input means, a count relay including a

winding and a contact set operative responsive to receipt of an impulse over said input means, and an associated sequence relay having a winding series-coupled with both the contact set and the winding of its respective count relay to effect operation of a given sequence relay responsive to operation of its respective count relay; a first contact set on each of said sequence relays coupled between said forward drive conductor and the winding of the count relay in the next higher block to prepare an operating circuit for said next higher count relay responsive to operation of said given sequence relay; a second contact set on each of said sequence relays coupled between said reverse drive conductor and the winding of the count relay in the next lower block to prepare an operating circuit for said next lower count relay responsive to operation of said given sequence relay; and means for selectively applying an impulse over one of said drive conductors to one of said prepared operating circuits to operate an alternative one of said next higher and next lower count relays.

5. A counting chain comprising: a pair of supply conductors; a forward drive conductor connected for selective coupling to one of said supply conductors to transmit forward impulses over said forward drive conductor; a reverse drive conductor connected for selective coupling to said one supply conductor to transmit reverse impulses over said reverse drive conductor; means for applying a potential difference across said supply conductors; a plurality of counting chain blocks, each of said blocks comprising input means, a count relay including a winding and a contact set operative responsive to receipt of an impulse over said input means, and an associated sequence relay having a winding series-coupled with both the contact set and the winding of its respective count relay to effect operation of a given sequence relay responsive to operation of its respective count relay; a first contact set on each of said sequence relays coupled between said forward drive conductor and the winding of the count relay in the next higher block to prepare an operating circuit for said next higher count relay responsive to operation of said given sequence relay; a second contact set on each of said sequence relays coupled between said reverse drive conductor and the winding of the count relay in the next lower block to prepare an operating circuit for said next lower count relay responsive to operation of said given sequence relay; and means for selectively coupling said forward and reverse drive conductors to said one supply conductor to transmit an impulse to one of said prepared operating circuits to operate an alternative one of said next higher and next lower count relays.

6. A counting chain comprising: a plurality of counting chain blocks, each of said blocks comprising input means, a count relay operative responsive to receipt of an impulse over said input means, and an associated sequence relay connected for operation responsive to operation of its respective count relay; a first contact set operable by each of said sequence relays to prepare an operating circuit for the next higher count relay responsive to operation of a given one of said sequence relays; a second contact set operable by each of said sequence relays to prepare an operating circuit for the next lower count relay responsive to operation of said given sequence relay; and means for presetting a desired number on the counting chain.

7. A counting chain comprising: a plurality of counting chain blocks, each of said blocks comprising input means, a count relay operative responsive to receipt of an impulse over said input means, and an associated sequence relay connected for operation responsive to operation of its respective count relay; a first contact set operable by each of said sequence relays to prepare an operating circuit for the next higher count relay responsive to operation of a given one of said sequence relays; a second contact set operable by each of said sequence relays to prepare an operating circuit for the next lower count relay responsive to operation of said given sequence relay; and preset means for selectively applying an impulse to a preselected one

of said count relays to operate said one count relay and thereby preset a desired number on the counting chain.

8. A counting chain comprising: a pair of supply conductors; a forward drive conductor connected for selective coupling to one of said supply conductors to transmit forward impulses over said forward drive conductor; a reverse drive conductor connected for selective coupling to said one supply conductor to transmit reverse impulses over said reverse drive conductor; a preset conductor connected for selective coupling to said one supply conductor to transmit a preset impulse over said preset conductor; means for applying a potential difference across said supply conductors; a plurality of counting chain blocks, each of said blocks comprising input means, a count relay including a winding and a contact set operative responsive to receipt of an impulse over said input means, and an associated sequence relay having a winding series-coupled with both the contact set and the winding of its respective count relay to effect operation of a given sequence relay responsive to operation of its respective count relay; preset means for selectively coupling said preset conductor to the input means of a given one of said count relays to effect operation of said count relay and its associated given sequence relay to insert a preset number on the counting chain; a first contact set on said given sequence relay coupled between said forward drive conductor and the winding of the count relay in the next higher block to prepare an operating circuit for said next higher count relay responsive to operation of said given sequence relay; a second contact set on said given sequence relay coupled between said reverse drive conductor and the winding of the count relay in the next lower block to prepare an operating circuit for said next lower count relay responsive to operation of said given sequence relay; and means for selectively coupling said forward and reverse drive conductors to said one supply conductor to transmit an impulse to one of said prepared operating circuits to operate an alternative one of said next higher and next lower count relays and thereby effect alternatively addition and subtraction of a single digit from said preset number.

9. A counting chain comprising: a units bank including a plurality of counting chain blocks, each of said blocks comprising input means, a count relay operative responsive to receipt of an impulse over said input means, an associated sequence relay connected for operation responsive to operation of its respective count relay, a first contact set operable by each of said sequence relays to prepare an operating circuit for the next higher count relay responsive to operation of a given one of said sequence relays, and a second contact set operable by each of said sequence relays to prepare an operating circuit for the next lower count relay responsive to operation of said given sequence relay; and a tens bank comprised of a like number of counting chain blocks connected in like manner, and further including means for transmitting an additive impulse to the tens bank responsive to registration of each tenth additive impulse on the units bank, and for transmitting a subtractive impulse to the tens bank responsive to registration of each tenth subtractive impulse on the units bank.

10. A counting chain comprising: a units bank including a plurality of counting chain blocks, each of said blocks comprising input means, a count relay operative responsive to receipt of an impulse over said input means, an associated sequence relay connected for operation responsive to operation of its respective count relay, a first contact set operable by each of said sequence relays to prepare an operating circuit for the next higher count relay responsive to operation of a given one of said sequence relays and a second contact set operable by each of said sequence relays to prepare an operating circuit for the next lower count relay responsive to operation of said given sequence relay; and a tens bank comprised of a like number of counting chain blocks connected in like

manner, and further including a tens forward relay which is prepared for operation responsive to operation of the last sequence relay in the units bank and which is thereafter operated responsive to operation of the first count relay in said units bank, and a tens reverse relay which is prepared for operation responsive to operation of the first sequence relay in said units bank and which is thereafter operated responsive to operation of the last count relay in said units bank.
